UNITED STATES PATENT OFFICE.

CANDACE WHEELER, OF JAMAICA, NEW YORK.

DESIGN FOR HANGINGS, COVERINGS, &c.

SPECIFICATION forming part of Design No. 16,469, dated January 12, 1886.

Application filed June 10, 1885. Serial No. 162,983. Term of patent 3½ years.

To all whom it may concern:

Be it known that I, CANDACE WHEELER, of Jamaica, Queens county, Long Island, New York, have invented a new and original Design for Hangings, Upholstery, &c., of which the following is a specification, reference being had to the accompanying drawing.

My invention relates to a new and original design to be worked into or upon fabrics, paper, &c., for use in hangings, upholstery, wall-coverings, &c.; and it consists of the novel grouping and configuration of figures herein fully described and shown.

The drawing illustrates a face view of a fabric having my new design.

The design consists in a certain combination of leaves and stem-work with the fruit of the pomegranate. One figure, *a*, contains a number of leaves radiating from a point at about the middle of the base of the figure. From this same point two stems, one on either side, pass around the figure, inclosing the leaves, and, coming within a short distance of each other at the top, curve upward, so as to become about parallel, then curve outward again, and continue to curve in the same direction until a circle has been nearly completed. From this end of the stem spring smaller stems, supporting pomegranates, three hanging within the small circle, and one without. The general appearance of this figure, omitting the fruit, is like that of a vase with a broad flat body, a narrow neck, and with the flange of the vase at the top greatly widened and curved down and in upon the body. These figures are continuous, one vase-shaped figure above another, in such way that the two stems forming the base of one figure rest upon the two stems forming the mouth of the figure below. On either side of this row of figures is another row of figures, *b*, similar to the first in general form and character, but differing from it in the following particulars: The same vase

form with the pendent pomegranates at the top is retained; but the vase is narrower, the radiating point of the leaves is raised to within a short distance of the center of the body, the number of leaves is increased, some hanging downward, the top of the body tapers more gradually into the neck, the neck is narrower and higher, and, lastly, the stems forming the outlines of the vase-forms are now continuous, the two stems forming the mouth of one vase-form no longer curving around to form a circle, but running into the two stems, respectively, that form the base of the vase-shaped figure above, and the stems that support the pomegranates being offshoots springing from the sides of the neck and curving downward, with the convexity toward the body of the vase-shaped figure, and then upward, giving off stems that support the fruit—three within the small circle and one without, as before. These two distinct rows of figures alternate with each other across the width of the design, and are so placed that the neck of a vase-shaped figure in one row is on a level with the body of a vase shaped figure in the next row. The characteristic feature of my design is the vase-shaped figure made of leaves and stem-work, and having pendent pomegranates in groups of four, three within and one without the circle.

What I claim as new, and desire to secure by Letters Patent, is—

The design for goods for hangings, upholstery, wall-coverings, &c., said design consisting of a representation of leaves, stem-work, and the fruit of the pomegranate, combined and arranged substantially as shown and described.

CANDACE WHEELER.
